BONE CONDUCTION AUDIPHONE

William A. Zarth, Jamaica, N. Y., assignor to
Dictograph Products Company, Inc., New York,
N. Y., a corporation of Delaware

Application April 8, 1939, Serial No. 266,757

8 Claims. (Cl. 179—107)

This invention relates to audiphones, and has particular reference to bone conduction audiphones having a vibratory member adapted to be placed in operative connection with the bone structure of the user for transmitting therethrough to the inner ear the audible sounds picked up by a suitable microphone.

In general, the prior bone conduction audiphones may be divided into two classes. In one class, the electromagnetic means is supported by a headband or the like, with its vibratory member held in operative connection with the bone structure of the user, so that the vibrations thereof across the magnetic gap are normal to the bone it engages and are applied directly thereto. An example of this type of audiphone is illustrated in Patent No. 2,144,458, issued January 17, 1939, to Henry Koch. In the other class of bone conduction audiphones, the vibratory member of the electromagnetic means is supported by a headband or the like, with the relatively massive part of the electromagnetic means floatingly mounted with respect thereto, so that while the vibrations across the air gap are normal to the bone surface, they are applied indirectly thereto, being reactive vibrations of the vibratory member relatively to the said massive part because of the high relative inertia of the latter. An example of this class of audiphone is illustrated in Patent No. 2,148,024, issued February 21, 1939, to Henry Koch. While both classes of audiphones have proven generally satisfactory, there are certain objections to each. For example, with the first or direct-acting class, the free vibrations of the reed connected to the vibratory member are liable to be suppressed to a certain degree by reason of the contact of the latter with the bone, unless the headband pressure and the resilient connections between the relatively vibrating parts are carefully proportioned, although it has the advantage of low power expenditure. With the second or inertia reaction class, the relatively heavy masses which are desirable in order to secure the requisite vibration cause the expenditure of a considerable amount of power, although it has the advantage that neither the air gap nor the vibrations of the vibratory member are affected by pressure of the latter on the bone.

In accordance with the present invention, a bone conduction audiphone is provided which has certain distinct advantages over the aforementioned classes of bone conduction audiphones, embodies their principal advantages and does not embody their disadvantages. In a preferred embodiment of the invention, the vibratory member

adapted to be placed in operative connection with the bone structure of the user, carries an electromagnetic means having a vibratory element which vibrates independently of the member and in a direction generally parallel to the surface of the bone which the member engages, instead of normal thereto, as in the case of both classes of prior audiphones, whereby the vibrations of the member are not suppressed by its contact with the bone and the inertia of the parts is not relied on to provide the requisite vibration, so that less power is required.

More particularly, the audiphone of this invention comprises a contact plate serving as the vibratory member, to which is secured one side of a generally ring-shaped core slotted transversely at a point substantially opposite its point of connection with the member to form an air gap. The core is semi-flexible, so that the poles forming the air gap are movable relatively to each other in response to changes in the magnetic flux across the gap induced by voice currents traversing windings associated therewith. Inasmuch as this vibration is generally parallel to the vibratory member and engaged bone surface, the component thereof is transmitted through the connection between the core and the vibratory member, so that the latter vibrates with minute but powerful vibrations, which are transmitted through the bone to the inner ear of the user. A cover mounted on the contact plate or vibratory member encloses the electromagnetic means so that the entire unit vibrates bodily and may be resiliently supported by a headband or the like in the usual way.

In a modified form of the invention an armature, a second core extends normally to the face plate or vibratory member, with its end lying in the air gap of the core, thereby forming a generally E-shaped structure having two flux paths and two air gaps, each of the two flux paths so formed being shorter than the flux path of the first form.

It will be seen that the bone conduction audiphone of this invention is a very simple and effective device for securing efficient vibrations of the bone without expenditure of a large amount of power and without variation of the air gap, due to pressure of the receiver on the bone. Because the inertia of the electromagnetic means is not utilized during the operation of the new device, the mass thereof need not be great but only sufficient to provide an efficient flux path to secure the vibrations necessary for audible and intelligible audition.

For a more complete understanding of the invention, reference may be had to the accompanying drawing, in which:

Figure 1 is a longitudinal section through a preferred embodiment of the bone conduction audiphone of this invention, as seen along the line 1-1 of Fig. 2;

Fig. 2 is a plan view thereof with the cover removed;

Fig. 3 is a transverse section thereof as seen along the line 3-3 of Fig. 1;

Fig. 4 illustrates a modification of the form shown in Figs. 1 to 3, inclusive; and

Fig. 5 illustrates the manner of supporting the audiphone on a headband and the manner of connecting it in a microphone circuit.

Referring to Fig. 1 of the drawing, numeral 10 designates the contact plate, preferably of non-metallic material such as synthetic resin, having a relatively substantial area on the order of one square inch, and being relatively flat for placement in operative connection with the bone structure of the user to serve as the vibratory member which transmits vibrations to the inner ear through the bone structure of the user. The contact plate 10 may serve as a wall of a casing, the other walls of which are provided by a hollow cover 11 suitably attached to the contact plate 10 by screws passing through holes 12 shown in Fig. 2.

The upper or inner surface of the vibratory member of contact plate 10 is provided with a narrow, transversely-extending boss 13, which may be integral as shown in Figs. 1 and 3, or may be a washer or the like, as shown in Fig. 4. Mounted on this boss or washer 13 and rigidly secured by one side to plate 10 by tap screws 14 is a ring-shaped core 15 of magnetically-permeable or permanently magnetizable material, such as iron, soft steel, aluminum-nickel alloy, cobalt-iron alloy, or the like. The core 15 is not a completely closed ring but has a narrow transverse slot at a point substantially opposite the boss 13, so that the core is generally C-shaped, having two arms 16 and 17 extending laterally to either side of the boss 13 with their inwardly-turned ends forming respective pole pieces 18 and 19 at either side of the air gap 20, which has a width on the order of one thousandth of an inch, more or less.

The core 15 may be conveniently made in one piece of relatively wide flat stock, so that it is inherently semi-flexible in a vertical plane, permitting relative movement between the pole pieces 18 across the air gap 20 in a direction generally parallel to the surface of the contact plate 10. The flexibility of the core 15 about the boss 13 may be augmented by saw-cutting the core transversely as indicated at 21 in Fig. 1. By reason of their bow shape, the arms 16 and 17, though extending only a short distance from plate 10, produce the vibratory effect on base 10 of long straight arms upstanding from the base.

Mounted on the arms 16 and 17 of the core 15 are the voice coils 22 and 23, respectively. These coils 22 and 23 are oppositely wound and connected either in parallel or in series in such a way that, when traversed by voice currents, the flux across the air gap 20 is varied to cause relative vibration between the arms 16 and 17 of the core 15 in a direction substantially parallel to the surface of the contact plate or vibratory member 10.

The voice coils 22 and 23 are connected in the telephonic circuit, including a microphone 24, a

battery 25, as shown in Fig. 5, and preferably a suitable amplifier, not shown. Two contact prongs 26 in this circuit are adapted to be removably received in corresponding holes 27 in the cover 11, shown in Fig. 1. Extending into each of these holes 27 is a contact member 28 electrically connected by coil spring 29 to a connecting strip 30 on which the spring 29 rests. There are two such assemblies and corresponding connector strips 30, the latter being preferably inlaid flush with the inner surface of the contact plate 10 and having their ends 31 extending upwardly adjacent the coils 22 and/or 23, depending upon whether they are connected in parallel or in series. Light filamentary conductors 32 leading to and from the coils 22 and 23 are soldered or otherwise electrically connected to the ends of conducting strips 30. Accordingly, when the connector prongs 26 are inserted in the holes 27 they connect the coils 22 and 23 into the circuit of microphone 24.

As shown in Figs. 3 and 5, a headband 33 having a fork 34, whose pivot pins 35 are connected to the sides of the cover 11 adjacent the air gap 20, may be used for holding the contact plate or vibratory member 10 in operative connection with the mastoid eminence of the user, or some other part of his bone structure.

In operation of the bone conduction audiphone illustrated in Figs. 1 to 3, inclusive, the speech currents picked up by the microphone 24 and suitably amplified traverse the coils 22 and 23, causing variations in the flux traversing the core 15 and the air gap 20, with the result that the two arms 16 and 17 in effect pivot about the general center point of the core 15 adjacent the boss 13 so that the vibration between the poles 18 and 19 across the air gap 20 is in a direction generally parallel to the surface of the contact plate or vibratory member 10. Since the amplitude of this vibration is small, the component thereof, which is the useful vibration transmitted to the contact plate of vibratory member 10, is so minute that it is practically unmeasureable. Nevertheless, the vibrations are powerful, and are readily heard and intelligible to deafened persons, it appearing that the comparatively large amplitudes of vibrations of the two classes of prior bone conduction audiphones being unnecessary to good bone audition.

In the modification illustrated in Fig. 4, the core 15' is constituted of several parts instead of being integral, as in Fig. 1, although the core of Fig. 1 may also be made up of several parts. Two L-shaped arms 16' and 17' are each secured at one of their ends to a magnetically permeable spring 36 secured at its center over spacing washer 13' to contact plate 10' by screws 14'. The other ends of the arms 16' and 17' are spaced from opposite sides of a center core 37 also mounted on spring 36 and forming with the poles 18' and 19' of respective arms 16' and 17' the two respective magnetic gaps 38 and 39. The entire core is accordingly generally E-shaped, as shown in Fig. 4.

In the modification of Fig. 4, but one voice coil 40 is employed and is mounted on the second core 37, although if desired two voice coils may be mounted on the two arms of the core 15' as shown in Fig. 1, and further, if desired, there may be three such coils, one on the second core 37, and two on the core 15', depending upon requirements.

In the arrangement of Fig. 4, the two flux

paths, one traversing arm 16', air gap 38, and center core 37, and the other traversing arm 17', air gap 39 and center core 37, are each shorter than the flux path traversing core 15 in Fig. 1 for equal flux density per unit of pole surface area. Also, the air gaps 38 and 39 may be made smaller than air gap 20 in Fig. 1 since, for the same amplitude of vibration of the arms 16, 17 and 16', 17', the vibration is divided between the two air gaps in the form of Fig. 4. The operation of the form of Fig. 4 will be readily understood from the description of the operation of Fig. 1, since they are essentially the same.

While certain preferred embodiments of this invention have been illustrated and described herein, it is to be understood that the invention is not limited thereby but is susceptible of variations in form and detail within the scope of the appended claims. For example, the cores 15 and 15' may be any shape with the speech coils mounted on the horizontal arms instead of the vertical arms, so long as the general direction of the vibration across the air gap is substantially parallel to the contact plate surface engaging the bone.

I claim:

1. In a bone conduction audiphone, the combination of a vibratory member having a relatively flat surface adapted to be operatively connected with the bone structure of the user, a pair of elements mounted on said member and extending a substantial distance in opposite lateral directions from their mounting on said member, said elements having inwardly turned end parts forming a narrow magnetic gap traversed by flux in a direction substantially parallel to said surface, said gap affording limited relative vibration between said parts substantially parallel to the surface of said member, and a winding associated with said elements for varying the magnetic flux traversing said elements and said air gap in response to voice currents, whereby the component of the commensurate relative vibration between said elements due to their leverage about said mounting is transmitted through at least one of said elements, the member and the connected bone structure to the inner ear of the user.

2. In a bone conduction audiphone, the combination of a vibratory member having a relatively flat contact surface, electromagnetic means comprising a core attached to said member and a winding thereon, said core having arms extending a substantial distance laterally to either side of the point of attachment with their ends turned inwardly to form a gap substantially opposite said point of attachment across which the said ends of said arms relatively vibrate about said point of attachment in a direction substantially parallel to said surface, and means for supporting said member with its said surface in operative connection with the bone structure of the user for transmitting the component of the said vibration through said core, the said point of attachment, said member, and said bone structure to the inner ear.

3. In a bone conduction audiphone, the combination of a vibratory member having a substantially flat contact surface, electromagnetic means comprising a core attached to said member and a winding thereon, said core having arms extending laterally in opposite directions a substantial distance and then upwardly from said member with their free ends turned inwardly to form a gap across which the said ends of said arms relatively vibrate in a direction substantial-

ly parallel to said surface, and means for supporting said member with its said surface in operative connection with the bone structure of the user for transmitting the component of the said vibration through said core, the said point of attachment, said member, and said bone structure to the inner ear.

4. In a bone conduction audiphone, the combination of a vibratory member having a relatively flat contact surface, electromagnetic means comprising a core attached to said member and a winding thereon, said core having a portion extending substantially parallel to said surface and secured to said member and arm portions extending substantially normal from said first portion in spaced relation with their free ends turned inwardly to form a gap across which the said ends of said arms relatively vibrate in a direction substantially parallel to said surface, said core having a transverse dimension parallel to said surface which is at least as great as its dimension normal to said surface, and means for supporting said member with its said surface in operative connection with the bone structure of the user for transmitting the component of the said vibration through said core, the said point of attachment, said member, and said bone structure to the inner ear.

5. In a bone conduction audiphone, the combination of a housing including a substantially flat contact plate adapted to be operatively connected with the surface of the bone structure of the user, electromagnetic means comprising a core and a winding thereon, said core having arms spaced apart a substantial distance and connected together at one end and secured at that end to said plate with their free ends spaced from said one end, extending substantially parallel to said plate and forming a gap traversed by flux in a direction substantially parallel to said plate, the association of said arms affording limited relative vibration between their free ends in response to variations in magnetic flux across said gap induced by voice currents traversing said winding, and means for supporting said plate in operative connection with said bone structure for transmitting the component of said vibration therethrough to the inner ear.

6. In a bone conduction audiphone, the combination of a vibratory member adapted to be operatively connected with the surface of the bone structure of the user, electromagnetic means comprising a core and a winding thereon, said core having a flattened C-shape and being secured to said member at its flattened side opposite the gap to form two opposite arms connected for relative vibration across said gap in response to variations in magnetic flux induced in said arms by voice currents traversing said winding, whereby the component of said vibration is transmitted through said member and connected bone structure to the inner ear.

7. In a bone conduction audiphone, the combination of a vibratory member adapted to be operatively connected with the surface of the bone structure of the user, electromagnetic means having a flattened C-shaped core secured to said member at its flattened side substantially opposite the gap to form two opposite arms connected for limited relative vibration across said gap, and windings on the arms of said core arranged for varying the magnetic flux across said gap when energized by voice currents to effect said relative vibration between the members,

whereby the component of said vibration is transmitted through the member and connected bone structure to the inner ear.

8. In a bone conduction audiphone, the combination of a vibratory member adapted to be operatively connected with the surface of the bone structure of the user, electromagnetic means having a flattened C-shaped core, means securing said core to the member at its flattened side substantially opposite the gap in the core to form

10

two opposite arms connected for limited relative vibration across said gap, and a winding on each arm, said windings being arranged to vary the magnetic flux across said gap when energized by voice currents to effect relative vibration between the members about said means, whereby the component of said vibration is transmitted through the member and connected bone to the inner ear.
